2,515,381

TYPEWRITER FOR PRINTING WITH THE
AID OF HEATHenry Resch, Bayonne, N. J., assignor to Ralph
C. Coxhead Corporation, New York, N. Y., a
corporation of Delaware

Application August 10, 1946, Serial No. 689,753

14 Claims. (Cl. 197—6.5)

1 This invention relates to typewriters. Certain features of the invention are particularly applicable to typewriters adapted to write on surfaces such as thermoplastic material and other material upon which it is difficult to form type impressions with the ordinary typewriter.

In the past considerable difficulty has been experienced in forming printed impressions of type on thermoplastic material. However, it has been found possible to form such impressions by the use of heated type together with a specially constructed type ribbon. The invention is particularly applicable to a typewriter of the kind known in the trade as the "Variyper," the typewriter shown in the accompanying drawings and to be described herein being particularly adapted for typing on flexible plastic tubing such as that sold under the trade-name of "Vinylite."

An object of this invention is to provide a typewriter having means to heat the type.

Another object of the invention is to provide a typewriter having means to heat the material to be typed on and the type ribbon prior to the printing operation.

Another object of the invention is to provide controls for the type-and-material-heating means in order to regulate the degree of heat in accordance with the character of the material being typed on and the size of the type, and to prevent overheating of the type and the material with consequent damage thereto.

Another object of the invention is to provide a structure for typewriter carriages capable of holding elongated strands of material in position for typing thereon.

A further object of the invention is to generally improve typewriters.

Still further objects and advantages of the invention will appear as the description proceeds.

My invention is defined in the appended claims. In the claims as well as in the description parts are identified by specific names for convenience and such nomenclature is intended to be as generic in its application to similar parts as the prior art will permit. The best form in which I have contemplated applying my invention is illustrated in the accompanying diagrammatic drawings forming part of this specification in which:

Fig. 1 is a top plan view of the rear portion of the typewriter, including the carriage and the type, tubing being shown in position for receiving type impressions.

Fig. 2 is a right side elevation of a portion of the typewriter shown in Fig. 1, some of the parts being omitted for clarity of the parts described.

2 Fig. 3 is a right side elevation of the type-heating coils and associated parts at the printing point.

Fig. 4 is a top plan view showing the heating unit, the type shuttle being indicated.

Fig. 5 is a vertical section of the heating unit taken on the line 5—5 of Fig. 4.

Fig. 6 is a vertical section of the heating unit taken on the line 6—6 of Fig. 4.

Fig. 7 is a schematic wiring diagram of the electrical connections.

The present invention will be described as applied to a typewriter of the type known in the trade as a "Variyper," although the invention is capable with some modification of being applied equally well to other kinds of typewriters. The "Variyper" shown in the drawings is a model A produced by the Ralph C. Coxhead Corporation, modified as hereinafter described, but otherwise a standard commercial machine old in the art.

The typewriter shown and described has been designed particularly for permanent typing upon flexible small diameter "Vinylite" tubing of the type commonly used as terminal insulation for electrical connections. It is desirable to have the terminal insulation of complicated electrical wiring so marked that the individual wires may be readily identified at any later time. Accordingly, by typing appropriate characters on "Vinylite" tubing and subsequently cutting the tubing into short lengths positionable at terminal endings of wiring, a permanent positive means of identifying the wiring is provided. However, a typewriter embodying this invention is capable of a multiplicity of other uses as well as typing on such tubing.

In Fig. 1, a top plan view of the modified conventional typewriter is shown. The typewriter has a carriage generally indicated as 11 which is mounted on a guide 12 (see Fig. 2) for transverse movement in the conventional manner past a common printing point 14. The carriage 11 is operatively associated with suitable conventional mechanism, not shown, for progressing it past the printing point 14 as the individual type selecting levers, not shown, are actuated, effecting the typing operation. An anvil 15, fixed to the frame 16 of the typewriter has one or more shuttles 17, carrying embossed type, mounted thereon for movement about the periphery of the anvil under control of type keys for presenting selected characters of type at the printing point 14. A hammer 19 is actuated by a conventional mechanism, not shown, to drive the material 20, here shown as a flexible tube, against the selected type char-

acter.

3

acter to receive the type impressions. The hammer spring (not shown) is preferably slightly stronger than the standard spring normally used to supply the necessary force to collapse the material or tubing 20 into a plane surface against the shuttle 17 while forming the printed impression. A ribbon 21 is interposed between the material 20 and the type shuttle 17 in order to supply the necessary pigment for forming the type impression on the material 20. A conventional ribbon shield 22 is interposed between the material 20 and the ribbon 21. The shield 22 has an aperture at the printing point to permit the material 20 to contact the ribbon at a point opposite the selected type on type shuttle 17, the shield 22 serving to protect the material 20 from marking by the ribbon 21 elsewhere than at the printing point 14.

The ribbon shield 22 is conventionally mounted on arms 24 and 25 which are fixed in a frame 26 pivoted to the top plate 27 of the typewriter. This general organization of hammer, type shuttle, ribbon and type shield is old in the art and is shown and described more completely in Patent 2,007,229 of July 9, 1935, issued to Frank H. Trego, and 1,936,594 of November 28, 1933, issued to Charles A. Fuchs, to which reference is made for a more complete disclosure.

The material 20 is held in position on the carriage 11 by a pair of clamps 29 and 30. The clamps 29 and 30 are secured for common operation by means of upstanding lower flanges 31 and 32 to a transverse rod 34 which is journaled in brackets 35 and 36 mounted on a portion of the carriage 11. Collars 37, 37 are fixed to the transverse rod 34 adjacent brackets 35 and 36 to retain the rod 34 against longitudinal movement. Arms 39 project from the rear portion of the collars 37, each of which may comprise a relatively long screw threadedly engaged in the collar 37. A spring 40, see Fig. 2, is attached to the rear end of each of the arms 39, the opposite ends of the springs being anchored as by fixed screws 41. The effect of the springs 40, 40 is to urge the rod 34 and clamps 29 and 30 in a clockwise direction as viewed in Fig. 2, urging the upper ends 42 and 44 of clamps 29 and 30 respectively toward clamping abutments 45 and 46 of the carriage. A manually operable lever 47 may be fixed to an end of the rod 34 to turn the rod against the bias of springs 40 in order to withdraw the clamps and thereby release the tubing. Lever 47 preferably lies along one end of the carriage 11 and terminates in a flanged end 48 adapted to be manipulated by the typist. Accordingly, work may be inserted in the carriage or withdrawn therefrom by turning the lever 47 counterclockwise as viewed in Fig. 2, thus withdrawing the clamps 29 and 30 from holding position, after which the work to be held can be laid within the two clamps or withdrawn therefrom and the lever 47 released, the clamps serving to engage the strip material 20 and maintain it in a fixed position on the carriage 11 for passage past the printing point 14.

A heating unit generally indicated as 50 and comprising several individual coils, hereinafter described, is positioned adjacent the type shuttle 17 and supported by the frame 16 of the typewriter for applying heat for the printing operation. The heating unit 50 is preferably comprised in part of a flat arcuate segment 51, see Fig. 4. The segment 51 may be formed of a core 52 of heat resistant electrical insulating material wound with spaced turns of a continuous electrical resistance wire 54, such as Nichrome wire.

4

The arcuate segment 51 has side projections 55 and 56 adapted to be secured to a portion of the typewriter frame 16 in order to position the heating unit 50 against displacement. The arcuate segment 51 is preferably of substantially uniform width except at its mid-portion 57, where it is extended rearwardly somewhat, as best shown in Fig. 4 for a purpose to be described.

The heating unit 50 also has two upstanding arcuate segments 59 and 60 preferably having metal cores 61 and 62 formed with projecting flanges 63 and 64 adapted to be secured to the arcuate segment 51. Cores 61 and 62 may be covered with extended facings 65 of heat resistant electrical insulation projecting beyond the margins of the cores. The segments 59 and 60 are also wound with spaced turns of a single electrical resistance wire 66 and 67 of Nichrome or other suitable material, thereby forming heating coils. The wires 54, 66 and 67 are preferably connected in a single electrical series connection leading from terminal 68 to terminal 69 positioned at the extremities of the segment 51 and are electrically insulated from the typing mechanism. The segments 51, 59 and 60 are of the proper curvature and otherwise adapted to fit immediately below and about the anvil 15 and type shuttle 17 of the typewriter and serve to heat these parts, principally by convection and radiation. In addition, the extended mid-portion 57 of the segment 51 is adapted to underlie the front edge of the carriage 11 and heat the material 20 upon which the type impression is to be made immediately prior to the time it reaches the printing point, thus aiding in the printing operation, as will be hereinafter described. Further, the ribbon 21 is also heated by the heating unit 50 as it is progressed to the printing point 14.

A guide 70 is fixed to a portion of the frame 16 of the typewriter below the printing point 14 and the heating unit 50 and is projected rearwardly of the typewriter beyond the end of the segment 51. The lower portion of the guide 70 serves to reflect radiant heat from the heating unit 50 upwardly onto the anvil 15 and shuttle 17 in order to aid in heating these parts. Guide 70 has a bifurcated end portion 71 comprising 2 spaced fingers, one positioned on each side of the printing point, and bent forward to a point adjacent the ribbon shield 22. The extremities of the fingers 71 aid in maintaining the material 20 in proper position at the printing point 14 and serve as guides upon which the material 20 may slide when forced forwardly into contact with the ribbon 21 during the printing operation. The space between the two fingers 71 is sufficient to permit the hammer 19 to complete the printing stroke. Additionally, the guide 70 which receives heat from the heating unit 50 serves to conduct the heat to the material 20 in order to heat the material prior to progressing it to the printing point. The fingers 71 of the guide 70 at the printing point are slightly higher than the normal position of the material 20 lying within the clamps 29 and 30 in order to assure that the strip of material will remain in contact with the guide 70, any tension in the material 20 serving to hold it in firm contact with the guide.

The ribbon 21 is a thermosensitive type ribbon that is capable of forming type impressions only when the type, the ribbon and the material to be typed on, or at least one of them, are at an elevated temperature so as to soften the rib-

bon pigment or the surface of the material, or both, for the printing operation. A single use thermosensitive type ribbon known in the trade as branding tape, which is discarded after one passage past the printing point 14 has proved satisfactory for this purpose.

The ribbon feed mechanism for progressing the ribbon 21 past the printing point may be of any suitable type. The one shown is similar to that in Patent 2,161,856 of June 13, 1939, issued to Ralph C. Coxhead, to which reference is made for a more complete disclosure. The ribbon 21 is supplied from a conventional spool 12 located at the left of the machine after which it is passed about the guide roll 13. The ribbon 21 is then passed through a ribbon guide 14 past the printing point 14 adjacent the ribbon shield 22, through a second ribbon guide 15 and between the ribbon feed rolls 16 and 17 after which the ribbon is passed through a third ribbon guide 18 and discharged at the right side of the typewriter.

The degree of heat required depends to some extent upon the size of the type characters being used and upon the particular composition of material upon which the type impressions are to be formed. Variation in heating is provided for by a conventional rheostat 19 mounted at the rear of the typewriter and connected in electrical series with the resistance wires of the heating unit 50. The rheostat 19 is of the conventional variable resistance type, the amount of electrical current supplied to the heating unit 50 being regulated by setting the knob 80 to various positions.

To further control the supply of electrical energy to the heating unit 50, a conventional off and on electrical snap switch 81 is mounted on frame 16 and connected in series with the rheostat 19 and the heating unit 50. In addition, as a safety precaution, a thermostat 82 is positioned on the under side of the guide 10. The thermostat 82 may be of the enclosed conventional bimetallic element type containing a set of electrical contact points, the action of the thermostat being to open the electrical circuit passing through the heating unit 50 upon the guide 10 attaining an excessively high temperature. This thermostat is preferably set to open the circuit upon reaching a temperature of approximately 275° F. and is in the nature of a safety device only, not being operative unless the rheostat 19 is set so as to supply an excessive amount of electrical energy, all factors being considered, thus producing excessive heating of the shuttle 17 and the material 20 to be typed.

The electrical connections may be made as shown in Fig. 7, the electrical system being connected to a suitable source of electrical power, customarily 110 volt alternating current. The same source of power may be used that is used to drive the escapement and hammer resetting spring re-winding motor 83, such a motor being customarily used in this class of typewriters and more particularly described in the U. S. Patent 1,656,460 of January 17, 1928, issued to Arthur S. Wheeler, to which reference is made for a complete description thereof.

It will be apparent from a study of Fig. 7 that by maintaining the electrical switch 81 in an off-position the heating unit 50 is not energized. By substituting a conventional ribbon for the branding tape previously described, it is possible to use the same machine for conventional typing on strands of material and the like which

can be suitably engaged by the clamps 29 and 30.

If desired, a reel 84 may be mounted upon the left-hand end of the carriage 11 in order to hold the supply of strand material 20 upon which the typing operation is to be performed. By so mounting supply reel 84, the material can be withdrawn from the reel without cutting until after the typing operation is performed, thereby resulting in an economy of material inasmuch as the material cannot receive printed impressions adjacent the ends of the carriage where it is covered by the clamps 29 and 30. In such a modification, it is necessary to mount the reel 84 in such manner as not to interfere with the travel of the carriage to the right.

In order to form type characters along the center of different sizes of tubing or other strand material, the guide 10 may be made adjustable to regulate the height of the fingers 11 relative to the printing point, it being necessary to lower the fingers 11 for larger sizes of tubing. Adjustability may be secured by forming the vertical portion of each of the fingers 11 in two overlapping pieces clamped together by a nut and bolt 85 passing through a vertical slot in one piece and a hole in the other overlapping piece. By loosening its nut and bolt, each of the fingers 11 may be adjusted to the proper height to guide the material 20 to the printing point 14 so as to form the printed impression along the center thereof. After adjustment is completed, the nut and bolt 85 may be retightened. One or both of the clamps 29 and 30 may likewise be made adjustable in height to accommodate different sizes of tubing by adjustably securing a member 86 to the front face of the clamp by means of a thumbscrew 87 threadedly engaged in the clamp 30 and passing through a vertical slot in the member 86. A rearwardly turned flange 88 of member 86 serves as a guide for supporting the material 20 prior to engagement of the clamp 30 therewith.

While the invention has been described specifically as applied to a typewriter for typing upon "Vinylite" tubing, it is equally capable of typing upon other plastic surfaces, and compositions of material in which difficulty is experienced in typing with the conventional unheated type and usual ribbon. Accordingly, it will be understood that the invention is not confined to such typing operations, but is limited only as set forth in the accompanying claims.

What I claim is:

1. In a typewriter, means for selectively presenting type at a common printing point, means for progressing material to receive type impressions past the printing point, means including a thermosensitive type ribbon interposed between the type and the material during the printing operation for forming a printed impression of the type on said material, and means for heating said type and said material prior to forming the printed impression.

2. In a typewriter, means for selectively presenting type at a common printing point, means for progressing material to receive type impressions past the printing point, means including a thermosensitive type ribbon interposed between the type and the material during the printing operation for forming a printed impression of the type on said material, and means for maintaining said type at a predetermined elevated temperature and heating said material as it approaches the printing point.

3. In a typewriter, means for selectively pre-

senting type at a common printing point, means for progressing material to receive type impressions past the printing point, means including a thermosensitive type ribbon interposed between the type and the material during the printing operation for forming a printed impression of the type on said material, and electrical means for heating said type and said material prior to forming the printed impression.

4. In a typewriter, means for selectively presenting type at a common printing point, means for progressing material to receive type impressions past the printing point, means including a thermosensitive type ribbon interposed between the type and the material during the printing operation for forming a printed impression of the type on said material, and an electrical resistance heating element for heating said type and said material prior to forming a printed impression.

5. In a typewriter, means for selectively presenting type at a common printing point, means for progressing material to receive type impressions past the printing point, means including a thermosensitive type ribbon interposed between the type and the material during the printing operation for forming a printed impression of the type on said material, and an electrical resistance heating element positioned adjacent the printing point for maintaining said type at a predetermined elevated temperature and heating said material as it approaches the printing point.

6. A typewriter carriage for progressing strip material past a typewriter printing point in the direction of carriage movement, said carriage comprising: clamps mounted adjacent each end of the carriage and adapted to resiliently engage a cooperating portion of the carriage, strip material being positionable therebetween, means operable for disengaging said clamps and a reel mounted at the left end of said carriage and adapted to hold a supply of strip material.

7. In a typewriter, means for selectively presenting type at a common printing point, means for progressing material to receive type impressions past the printing point, means including a thermosensitive type ribbon interposed between the type and the material during the printing operation for forming a printed impression of the type on said material, and a thermostatically controlled electrical resistance heating element for maintaining said type at an elevated temperature and heating the material prior to the printing operation.

8. In a typewriter having a plurality of type symbols embossed on a common arcuate member and oscillatable on a vertical axis past a single printing point, means for selectively positioning the type symbols at the printing point, means for progressing material to receive type impressions past the printing point, means including a thermosensitive type ribbon progressed past the printing point and interposed between the type and the material during the printing operation for forming a printed impression of a type symbol on said material and an electrical resistance heating element positioned immediately below said type symbols for heating thereof.

9. In a typewriter having a plurality of type symbols positionable at a single printing point, means for selectively positioning the type symbols at the printing point, means for progressing material to receive type impressions past the printing point, means for forming a printed impression of a selected type symbol on said material, said last-mentioned means including a thermosensi-

tive type ribbon progressed past the printing point and interposed between the type and the material during the printing operation, and electrical resistance heating means positioned immediately below said type symbols and below said material adjacent to the printing point for maintaining said type symbols at an elevated temperature and heating said material in advance of forming the printed impression thereon.

10. In a typewriter having a plurality of type symbols embossed on a common arcuate member and oscillatable past a single printing point, means for selectively positioning the type symbols at the printing point, means for progressing material to receive type impressions past the printing point, means for forming a printed impression of a selected type symbol on said material, said last-mentioned means including a thermosensitive type ribbon progressed past the printing point, and an electrical resistance heating element positioned immediately below said type symbols and extending below said type ribbon and said material in the path of their advance to the printing point for maintaining said type symbols at an elevated temperature and heating said ribbon and said material in advance of the printing operation.

11. In a typewriter having a plurality of type symbols embossed on a common arcuate member and oscillatable on a vertical axis past a single printing point, means for selectively positioning the type symbols at the printing point, means for progressing material to receive type impressions past the printing point, means, including a thermosensitive type ribbon progressed past the printing point and interposed between the type and the material during the printing operation, for forming a printed impression of a type symbol on said material, and an electrical resistance heating element positioned immediately below the type member and extending beneath the type ribbon adjacent the printing point for heating the type symbols and the type ribbon.

12. In a typewriter having a plurality of type symbols embossed on a common arcuate member and oscillatable on a vertical axis past a single printing point, means for selectively positioning the type symbols at the printing point, means for progressing material to receive type impressions past the printing point, means, including a thermosensitive type ribbon progressed past the printing point and interposed between the type and the material during the printing operation, for forming a printed impression of a type symbol on said material, and an electrical resistance heating element positioned immediately below the type member and extending beneath the material and the type ribbon adjacent the printing point for heating the type symbols, the material, and the type ribbon.

13. A typewriter having a movable carriage for supporting material to be typed on, means for progressing the carriage past a common printing point, an anvil, a shuttle slidable along the surface of the anvil and having a face embossed with type characters selectively indexable at the printing point, means, including a thermosensitive type ribbon, for forming a printed impression of the indexed type on the material supported by the carriage, and an electric resistance heating element extending along at least a portion of the face of the type shuttle exterior of the anvil and shuttle for heating the type to condition it for forming a type impression.

14. A typewriter having a movable carriage

for supporting material to be typed on, means for progressing the carriage past a common printing point, an anvil, a shuttle slideable along the surface of the anvil and having a face embossed with type characters selectively indexable at the printing point, means, including a thermosensitive type ribbon, for forming a printed impression of the indexed type on the material supported by the carriage, and an electric resistance heating element extending along the face of the type shuttle at each side of the printing point and exterior of the anvil and shuttle for heating the type to condition it for forming a type impression.
